(57) **CLAIM**

The ornamental design for a bottom rail anchor assembly for corded window shades, as shown and described.

DESCRIPTION

FIG. 1 is a perspective view of a bottom rail anchor assembly for corded window shades;

FIG. 2 is a plan view thereof;

FIG. 3 is a bottom view thereof;

FIG. 4 is a front view thereof;

FIG. 5 is a back view thereof;

FIG. 6 is a left side view thereof;

FIG. 7 is a right side view thereof;

FIG. 8 is an exploded perspective view of FIG. 1;

FIG. 9 is a perspective view of the housing portion of the bottom rail anchor assembly for corded window shades of the design of FIG. 1;

FIG. 10 is a plan view of FIG. 9;

FIG. 11 is a bottom view of FIG. 9;

FIG. 12 is a front view of FIG. 9;

FIG. 13 is a side view of FIG. 9;

FIG. 14 is a perspective view of the spool portion of the bottom rail anchor assembly for corded window shades of the design of FIG. 1;

FIG. 15 is a top plan view of FIG. 14;

FIG. 16 is a bottom view of FIG. 14;

FIG. 17 is a front view of FIG. 14;

FIG. 18 is a back view of FIG. 14;

FIG. 19 is a left side view of FIG. 14;

FIG. 20 is a right side view of FIG. 14;

FIG. 21 is a perspective view of the bottom rail anchor assembly for corded window shades of the design of FIG. 1 shown in a position of use on the bottom rail of a window shade;

FIG. 22 is an exploded perspective view thereof;

FIG. 23 is a perspective view of the bottom rail anchor assembly for corded window shades of the design of FIG. 1 shown inverted in a position of use on the bottom rail of a full window shade assembly;

FIG. 24 is a top plan view thereof;

FIG. 25 is a bottom view thereof;

FIG. 26 is a front view thereof; and,

FIG. 27 is a side view thereof.

The broken lines in FIGS. 21-27 depict environmental subject matter that forms no part of the claimed design.
